Primary Examiner — Thomas Johannes*Assistant Examiner* — Shawn T Gingrich**CLAIM**

The ornamental design for a coaxial compression connector, as shown and described.

DESCRIPTION

FIG. 1 is a side perspective view of a coaxial compression connector showing the front, top, and left of my new design; FIG. 2 is a side perspective view thereof showing the rear, top and right of my new design; FIG. 3 is a side view thereof; FIG. 4 is a front view thereof; and, FIG. 5 is a rear view thereof.

The broken line portions of the figure drawings are included to show unclaimed subject matter only and form no part of the claimed design.
